FIG. 6.

Inventor

Joseph A. Williams.

Patented Dec. 30, 1924.

1,520,897

UNITED STATES PATENT OFFICE.

JOSEPH A. WILLIAMS, OF ANGIER, NORTH CAROLINA.

CLOTHES-WASHING APPARATUS.

Application filed July 11, 1923. Serial No. 650,831.

To all whom it may concern:

Be it known that I, JOSEPH A. WILLIAMS, a citizen of the United States, residing at Angier, in the county of Harnett and State 5 of North Carolina, have invented new and useful Improvements in Clothes-Washing Apparatus, of which the following is a specification.

The present invention relates to improvements in apparatus for washing clothes, and particularly to apparatus of the character or type which is commonly employed in country districts, where the apparatus is associated with a specially constructed furnace or heating means.

Among the objects of the invention may be mentioned that of providing means whereby the washing water may be heated in a minimum amount of time and the 20 clothes subjected to a thorough circulation of water.

A further object is to provide means by which the supply of water employed may be readily changed without interfering with 25 the washing operation, a suitable amount of clean water being constantly maintained.

In the drawings:—

Figure 1 is an end elevation of a washing apparatus embodying the invention.

Figure 2 is a longitudinal vertical section.

Figure 3 is a transverse section substantially on the line 3—3 of Figure 2.

Figure 4 is a horizontal section substantially on the line 4—4 of Figure 2.

Figure 5 is a bottom view of the cover plate detached.

Figure 6 is a detail, on an enlarged scale, of one of the pins of the cover plate.

Referring to the drawings, in the several views of which like reference characters designate corresponding parts, it will be seen that the embodiment of the invention illustrated comprises a furnace structure 1 45 formed of suitable brick or masonry, having a fire box which is closed at one end by a suitable door 2, and is provided at its opposite end with an upwardly extending stack 3.

A receptacle 4 is suitably supported within the furnace structure. As shown, this receptacle is formed of metal, being substantially rectangular in shape, and provided at opposite sides with laterally projecting 55 hangers 5, which are suitably engaged with

the walls of the furnace and support the receptacle firmly in position therein.

The bottom of the receptacle is formed with a plurality of relatively deep channels 6, which extend throughout the length of 60 the receptacle and the depending side walls of which are substantially vertical, thus forming a plurality of heating flues extending longitudinally of the fire box and communicating at the rear end with the 65 stack 3. The depth of the channels 6 is such that a relatively large heating surface is provided, and the water in said channels and the lower portion of the receptacle 4 will be quickly heated and caused to 70 circulate through the receptacle and clothes placed therein.

To assist in the circulation of the water through the clothes, it is preferred to arrange on the upper face of the bottom of the receptacle a series of parallel strips or plates 7, which extend across the receptacle from side to side and provide a plurality of openings communicating with each of the depending water channels 6. The number of 75 said plates or strips may be varied to suit circumstances, but preferably they are arranged relatively close together so that the openings between them communicating with the channels are relatively small, which acts 80 to assist the circulation of the water and cause it to move upwardly into the body of the receptacle with considerable force. The plates or strips 7 may be permanently secured to the bottom of the receptacle 4 by 85 any suitable means, such as rivets, welding, etc.

A pipe 8 connects the lower ends of the water channels 6, adjacent the stack end of the furnace, said channels being preferably slightly inclined downward toward 90 said pipe so that the receptacle and channels may be readily emptied when desired. A hand controlled valve 9 is provided by means of which the water may be readily withdrawn from the receptacle when desired. By opening the valve 9 and introducing a suitable water supply pipe into the receptacle, a circulation of water through the receptacle and channels 6 may be maintained 95 throughout the operation of the apparatus if desired, or the valve 9 may be operated to periodically withdraw the water from the receptacle either while fresh water is being introduced or otherwise.

Fitted within the receptacle 4 is a suitable cover plate 12. This plate extends over substantially the entire area of the receptacle, resting on the clothes therein and under the action of the steam pressure generated when the apparatus is in use, said plate will be intermittently raised slightly, permitting the escape of steam. It is preferably provided with a suitable weight 13, which will return it to its lower position on the clothes in the receptacle after each escape of steam pressure therefrom. It is preferred to employ a detachable weight for returning the plate to its lower position instead of depending on the weight of the plate alone, as this affords means for varying the weight opposed to the steam pressure generated when the apparatus is in use.

On the lower surface, the cover plate is provided with a series of depending pins 14, which extend downward into the body of the receptacle and contact with the clothes therein during the washing operation. The alternate rising and falling movement of the cover plate therefore causes said pins to exert a pounding-like action on the clothes during the washing operation. This action is further assisted by forming each of the pins 14 with a cavity or recess at its free lower end, thus in effect providing a series of vacuum cups on the cover plate by which the washing operation is greatly facilitated. The pins 14 are so spaced and related that they are out of alignment with the openings between the strips 7 that communicate with the depending channels 6.

It is believed that the operation and advantages of the present invention will be readily understood from the foregoing description and the drawings. It will be seen that the draft of the furnace can be readily regulated by adjustment of the fire box door 2, and owing to the shape of the receptacle and particularly of the depending channels at the bottom thereof, a maximum amount

of heating surface is provided so that the water in the receptacle will be quickly heated to the desired temperature.

When the apparatus is in use the cover plate 12 will be caused to alternately rise above the clothes on which it rests, by steam acting on its lower face. As soon as the body of the plate passes above the level of the upper edges of the receptacle the steam beneath it will escape and, by gravity, the weighted cover plate will fall back upon the clothes thus producing a pounding effect through the medium of the pins 14. It will be noted that the pins are so related to the apertures in the bottom through which the water enters the receptacle proper, that there is no danger of such openings being closed by the pins forcing any of the clothes in the receptacle thereinto. That is, the pins are arranged out of alignment with such water supply openings.

As before explained, a circulation of water through the apparatus may be constantly maintained if desired, and thereby the delays incident to emptying and refilling the receptacle with clean water may be avoided.

The reciprocation of the cover plate produces a pounding action on the clothes materially assisting in circulating the water through them.

Having thus described the invention, what is claimed and desired to be secured by Letters Patent is:—

An apparatus for washing clothes comprising a receptacle open at its top, and a removable cover plate fitted within the receptacle to move vertically therein and provided with a series of pins that extend downward into the body of the receptacle into contact with clothes placed therein, each pin having a cavity formed at its inner end, for the purpose described.

In testimony whereof I have hereunto set my hand.

JOSEPH A. WILLIAMS.
